CLAIM

The ornamental design of a bike deflector, as shown and described.

DESCRIPTION

FIG. 1 is a perspective view of the bike deflector of the present invention;

FIG. 2 is a right side elevational view, the left side elevational view being a substantial mirror image thereof;

FIG. 3 is a front elevational view thereof;

FIG. 4 is a rear elevational view thereof;

FIG. 5 is a top plan view thereof; and,

FIG. 6 is a bottom plan view thereof.

The broken line structure shown in the FIG. 1 drawing view is for illustrative purposes only and form no part of the claimed design.
